Primary Examiner — Keith J Wilson(74) *Attorney, Agent, or Firm* — Andrew C. Cheng(57) **CLAIM**

The ornamental design for a shower head, as shown and described.

DESCRIPTION

FIG. 1 is a bottom perspective view of a shower head, showing my new design;

FIG. 2 is a top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of encircled portion 9 of FIG. 1. The broken lines depict portions of the shower head that form no part of the claimed design. The dot-dash-dot lines represent boundaries of the enlarged view and form no part of the claimed design.
